US00D928008S

(12) **United States Design Patent** (10) Patent No.: **US D928,008 S**
(45) Date of Patent: **** Aug. 17, 2021**

(54) **WATCH DIAL**

(71) Applicant: **LVMH SWISS MANUFACTURES SA**, La Chaux-de-Fonds (CH)

(72) Inventor: **Guillaume Rochat**, Neuchatel (CH)

(**) Term: **15 Years**

(21) Appl. No.: **35/509,185**

(22) Filed: **Sep. 5, 2019**

(80) **Hague Agreement Data**

Int. Filing Date: **Sep. 5, 2019**

Int. Reg. No.: **DM/207325**

Int. Reg. Date: **Sep. 5, 2019**

Int. Reg. Pub. Date: **Apr. 24, 2020**

(30) **Foreign Application Priority Data**

Mar. 15, 2019 (WO) IBDM/200837

(51) **LOC (13) Cl.** **10-07**

(52) **U.S. Cl.**

USPC **D10/126**

(58) **Field of Classification Search**

USPC D10/126, 39; D11/43, 79

CPC B44C 1/105

See application file for complete search history.
